UNITED STATES PATENT OFFICE

2,133,798

APPARATUS FOR DISTRIBUTING GRANULAR OR PULVERULENT MATERIAL

Joseph S. Bennett, Merion, Pa., assignor to American Engineering Company, Philadelphia, Pa., a corporation of Pennsylvania

Application January 10, 1936, Serial No. 58,444

8 Claims. (Cl. 193—2)

This invention relates to material distributing apparatus, and more particularly to apparatus for distributing granular or powdered materials among a plurality of feeding devices.

5 One object of the present invention is to provide generally improved distributing apparatus for granular or pulverulent materials.

Another object is to provide improved apparatus for evenly distributing fuel, such as coal, coke, 10 10 and cinders, among a series of stoker feeding devices so that the fuel fed to the furnace will be substantially uniform throughout.

Another object is to provide improved material chutes having compartments therein for receiving 15 materials of different kinds, the chutes being so constructed as to evenly distribute materials among a series of receiving devices.

Other and further objects will become apparent as the description of the invention progresses.

20 Of the drawings:

Fig. 1 is a side elevational view of a stoker furnace showing one form of distributing means associated therewith.

Fig. 2 is a sectional elevational view of one of 25 the stoker fuel feeding devices and the associated hopper, showing a portion of the distributing apparatus.

Fig. 3 is a front elevational view partly in section taken substantially along line 3—3 of Fig. 1.

30 Fig. 4 is a plan view of the apparatus shown in Fig. 3.

Fig. 5 is a front elevational view partly in section of an alternative construction.

Fig. 6 is a sectional view taken substantially 35 along line 6—6 of Fig. 5, and

Figs. 7, 8 and 9 are sectional views taken substantially along lines 7—7, 8—8, and 9—9 respectively, of Fig. 5.

Referring to the drawings, the numeral 1 designates generally, a furnace equipped in the present instance with a multiple retort, underfeed stoker 2. Stoker 2 comprises the usual alternately disposed retorts 3 and tuyère rows 4. Fuel is supplied to the stoker 2 from a hopper 5 disposed near the front end thereof, and a series of rams 6 operating in cylinders 7 feed predetermined amounts of the fuel gravitating into the cylinders from said hopper upon each reciprocation thereof. The bottom of each retort 3 comprises a series of fuel feeding pushers 8 which underfeed the fuel in the retorts in a well known manner. The rams 6 and pushers 8 are operated by any suitable power mechanism 9, they being operatively connected thereto by a link and lever mechanism indicated generally by the numeral 10. Hopper 5 is provided with a partition 11 which divides the space therein into two compartments 12 and 13, the former of which may receive coal or coke from a chute 14, while the

latter may receive cinders or powdered fuel from spouts 15, as will appear more fully hereinafter.

Fig. 2 shows a ram 6 in its advanced position. Upon recession thereof, after a feeding operation, the fuel in compartment 13 will first gravitate into the cylinder 7, after which fuel from compartment 12 will enter said cylinder. As the ram is then actuated in the feeding direction the heavier materials gravitating in the cylinder from compartment 12 will be pushed over the lighter materials, as shown in Fig. 2. The lighter fuel, being thus covered by a layer of heavier fuel, will not be blown from the grates by the draft air, and as a result complete combustion of all of the fuel fed to the furnace is assured. Chutes 14 15 may be of the conical type shown and described in United States Patent No. 1,947,011, and each receives fuel from overhead bunkers (not shown) through a spout 16. By this construction the large and small particles of fuel gravitating into 20 each chute are evenly distributed over the entire width of the discharge end thereof, and consequently each of the associated fuel feeding devices receives an equal quantity of fuel.

The apparatus for distributing cinders or powdered fuel to compartment 13 of hopper 5 consists of a receiving chamber 17 which receives materials from any suitable hopper (not shown) through a spout 18. Chamber 17 comprises a frustro-conical casing 19 having a conical distributing member 20 mounted therein in spaced relation with the walls thereof. Chamber 17 is therefore of substantially conical form, having an annular discharge opening at the lower end thereof. The upper ends of spouts 15 are secured to a flange 21 of casing 19 and communicate with the discharge end of chamber 17. As shown more particularly in Figs. 3 and 4, the spouts 15 are so arranged that the lower or discharge ends thereof enter the upper end of compartment 13 directly over the cylinders 7. By this arrangement, it is seen that the fuel gravitating into chamber 17 is evenly distributed therein, and as a result equal quantities of fuel will enter each of the spouts 15 and be discharged into compartment 13 of hopper 5 in such a manner that each ram 6 will feed an equal quantity of cinders or powdered fuel upon each reciprocation thereof. Inasmuch as the chutes 14 communicating with compartments 12 also evenly distribute the heavier and lighter particles of fuel, among the cylinders 7 associated therewith, the fuel fed to each section of the stoker will be substantially uniform throughout.

Figs. 5 to 9 inclusive show an alternative construction for distributing materials of different kinds among each of a series of feeding devices. This construction comprises a chute 22 having downwardly inclined, substantially conical top and bottom walls 23 and 24 respectively, and 60

downwardly diverging side walls 25. A substantially conical partition 26 is mounted between top and bottom walls 23 and 24 dividing the interior of chute 22 into compartments 27 and 28, the 5 former of which may, in the present instance, receive cylinders or powdered fuel, while the latter, coal or coke. Top and bottom walls 23 and 24, and partition 26 terminate at the lower ends thereof in vertical extensions 29, 30 and 31 10 respectively, forming with the end walls 32 vertical discharge passages 33 and 34 for compartments 27 and 28. Substantially cylindrical extensions 35 and 36 are secured to the upper end of chute 22 in any suitable manner, forming inlet 15 passages to compartments 27 and 28 respectively. The discharge passages 33 and 34 of chute 22 communicate respectively with the compartments 37 and 38 of a hopper 39. The fuel supplied to hopper 39 gravitates into cylinders 40, and is fed 20 to the furnace by the rams 41 operating therein, as previously described.

The top and bottom walls 23 and 24, as well as partition 26 incline downwardly at an angle somewhat greater than the angle of repose, and by 25 virtue of the conical construction thereof the materials gravitating in compartments 27 and 28 will be evenly distributed across the entire discharge end of the chute.

While the embodiments herein described are 30 admirably adapted to fulfill the objects primarily stated, it is to be understood that the invention is not limited thereto, since it may be embodied in other forms, all coming within the scope of the claims which follow.

35 What is claimed is:

1. In a device of the class described, the combination of a chute comprising upper and lower walls of substantially conical form, and downwardly diverging side walls, a substantially conical partition disposed between said upper and lower walls dividing said chute into two compartments adapted to receive materials of different kinds, means defining inlet passages for each of said compartments, and extension means defining discharge passages for said compartments. 40

2. In a device of the class described, the combination of a chute comprising upper and lower walls of substantially conical form and downwardly diverging side walls, a substantially conical partition disposed between said upper and lower walls and in substantially parallel relation therewith dividing said chute into two compartments adapted to receive materials of different kinds, means defining inlet passages for each of said compartments, and extension means defining discharge passages for said compartments. 45

3. A chute for conveying granular or pulverulent materials comprising, upper and lower substantially conical walls, and diverging side walls, 60 a partition disposed between said upper and lower walls dividing the chute into compartments, means defining inlet openings for each of said compartments, and substantially vertical extensions provided at the lower ends of said top and bottom walls and said partition, said extensions defining substantially vertical discharge passages 65 communicating with said compartments.

4. In a device of the class described, the combination of a chute having upper and lower walls of substantially conical form, and downwardly diverging side walls, means defining inlet 70 passages for said chute, and substantially vertical

extensions provided at the lower ends of said top and bottom walls defining a discharge passage for said chute, a second chute superimposed upon said first mentioned chute, having an upper wall of substantially conical form spaced from the 5 upper wall of said first mentioned chute, means defining an inlet opening for said second mentioned chute, and a substantially vertical extension provided at the lower end of the upper wall of said second chute providing a substantially vertical discharge passage therefor. 10

5. In a device of the class described, the combination of a series of material receiving devices, means including an inclined member having downwardly diverging side edges for evenly distributing materials of one kind among all of 15 said receiving devices, means connecting said distributing means with each of said receiving devices, means including a substantially conical member for evenly distributing materials of another kind among all of said receiving devices, and means connecting said last mentioned means with each of said receiving devices. 20

6. In a device of the class described, the combination of a series of material receiving devices, means including a conical member for evenly distributing materials of one kind among all of said receiving devices, means connecting said distributing means with each of said receiving devices, means including a conical member superimposed upon said distributing means for evenly 25 distributing materials of another kind among all of said receiving devices, and means connecting said last mentioned means with each of said receiving devices. 30

7. In a device of the class described, the combination with a series of material receiving devices, of apparatus for evenly distributing materials of different kinds among all of said receiving devices, said apparatus comprising an inclined 40 chute provided with a distributing member having downwardly diverging side edges for distributing materials of one kind among all of said receiving devices, a second means for distributing materials of another kind among all of said receiving devices, said last mentioned means including a chamber having a substantially conical member provided therein, said chamber having inlet and discharge openings provided therein, and spouts connecting said discharge openings 45 with said receiving devices. 50

8. In a device of the class described, the combination with a series of material receiving devices, of apparatus for evenly distributing material of different kinds among all of said receiving 55 devices, said apparatus comprising an inclined chute provided with a distributing element having downwardly diverging side edges for distributing materials of one kind among said receiving devices, means defining inlet and discharge openings for said chute, means connecting the discharge openings of said chute with said receiving devices, a second device for distributing materials of another kind among all of said receiving devices, said means comprising a chamber having a 60 substantially conical member provided therein, means defining inlet and discharge openings for said chamber, and a series of spouts connecting said discharge openings with said receiving devices. 65

JOSEPH S. BENNETT.
